INTERNAL-COMBUSTION ENGINE.

1,079,741.

Specification of Letters Patent.

Patented Nov. 25, 1913.

Application filed February 15, 1912. Serial No. 677,655.

To all whom it may concern:

Be it known that we, FRED D. CALKINS and ALFRED C. JOHNSON, citizens of the United States, and residents of Sunnyvale, in the county of Santa Clara and State of California, have invented certain new and useful Improvements in Internal-Combustion Engines, of which the following is a specification.

- 10 Our invention is an improvement in internal combustion engines, and has for its object the provision of simple, inexpensive means for controlling the admission and exhaust of the motive fluid, wherein a continuously-rotating valve having a large bearing surface is provided, separated from the explosion chamber of the engine by a water jacket, and arranged to automatically compensate for wear.
- 20 In the drawings, Figure 1 is a section on the line 1—1 of Fig. 2; Fig. 2 is a section on the line 2—2 of Fig. 1; Fig. 3 is a side view of the valve; and Fig. 4 is an end view of the seat or chamber section.
- 25 In the present embodiment of the invention, a cylindrical shell 1 is provided, and the said shell is jacketed at one end, the upper, as shown at 2, and is seated at its lower end over an opening 3 in the crank case 4. The lower end of the shell is flanged laterally, as indicated at 5, the flange resting on the crank case walls, and the said walls are thickened at the sides to form a seat 6. A crank shaft 7 is journaled in bearings 8 in the end walls of the crank case, and the shaft is provided with a crank 9, below the shell, and with a pulley 10, outside of the case. A sprocket wheel 11 is secured to the crank shaft, and a chain 12 connects the wheel to the valve to be described later. A cylinder 13 is arranged in the shell, the lower end thereof extending into the crank case through the opening 3, and the upper end is closed by a head 14 and the bore of the cylinder is reduced adjacent to the head, as shown at 15. A spark plug 16 of ordinary form is threaded into an opening in the cylinder at the reduced portion, and the said plug extends through an opening 17 in the shell wall. A piston 18 is slidable in the main portion of the cylinder, and the said

piston is connected to the crank 9 by means of a rod 19, engaging a transverse pin 20 in the piston at one end, and provided at the other with a sectional bearing 21, for engaging the crank.

The outer face of head 14 is recessed and formed into one section 22 of a bearing or valve chamber for the valve 23, and the other section 24 of the bearing or chamber is secured to the end of the cylinder by bolts or cap screws 25. The shell 1 extends beyond the section 22 of the bearing, and the said section is provided with aligned ports 26—26^a extending longitudinally of the valve (Fig. 4). The outer section of the chamber or bearing is jacketed, as shown at 27, and is provided with aligned ports 28, 28^a registering with ports 26, 26^a of the inner section. The outer section is also provided with approximately parallel transverse ports or passages 29, 29^a for placing the ports 28 and 28^a in communication with the exhaust and inlet manifolds respectively.

The valve 23 is in the shape of a cylinder or drum, and is rotatable in the chamber. The valve is provided at one end with a head 30 extending beyond the periphery of the drum, and seating against the end of the chamber or bearing to seal the said end. The valve is provided with an annular series 31 of sprocket teeth at the opposite end for engagement by a chain 12, to rotate the valve, and the valve extends beyond the adjacent end of the chamber or bearing to bring the series 31 of teeth into the same plane with wheel 11. The valve is also provided with two transverse ports 32 and 32^a extending diametrically of the valve, and arranged at an angle to each other, so that the ends of the ports are spaced apart angularly from each other. The ports 32 and 32^a are designed to connect ports 26 and 28 and ports 26^a—28^a respectively, twice during each complete rotation of the valve. The passages 29 and 29^a open at opposite ends of the valve chamber, the former being the exhaust and the latter the intake port. The inner section 22 of the valve chamber is integral with the cylinder 13, and the cylinder is movable longitudinally of the shell and the cylinder and bearing

section are pressed toward the outer section by means of an elbow lever composed of arms 34 and 35, and pivoted at 36 in the crank case. But one elbow lever is shown, 5 but preferably several are provided, and the arms 34 and 35 are of resilient material so that while the bearing or chamber sections are pressed together, there may be some yielding. One arm 34 of each lever 10 engages the lower edge of the cylinder and a set screw 37 is threaded through a bearing 38 in the crank case and engages the arm 35. A lock nut 39 is provided for locking the screw in adjusted position, and it 15 will be obvious that the pressure against the section may be regulated by the set screw. The bearing or chamber section 22 does not engage section 24, the said section seating against the end of the shell, and 20 the bearing or chamber sections are spaced apart, as shown at 40 in Fig. 1. Wear of the valve or bearing section may thus be compensated for. The piston as shown in Figs. 1 and 2 is at the limit of its outward 25 stroke, and the outer end thereof is near the inner end of the reduced portion of the cylinder bore. An explosion chamber 41 is thus provided between the piston and the head 14.

30 In operation, the valve is rotated continuously from the crank shaft, and twice during each rotation, port or passage 32^a connects inlet port 29^a with port 26^a to admit a charge to the explosion chamber. The 35 charge is drawn into the cylinder as the piston moves down and the return stroke of the piston compresses the charge which is ignited as the piston starts on its working stroke. On the return from the working 40 stroke, the exhaust charge is driven out through ports 26—32 and 29, the ports 26 and 29 being connected at the time through port or passage 32. The engine is a four-cycle engine, and the valve has a large bearing 45 surface, so that wear is reduced to a minimum. The valve does not become heated on account of the water jacket between the explosion chamber and the valve. The valve is also automatically compensating, 50 all wear being immediately taken up by the elbow lever. The sprocket wheel 11 and series 31 of teeth are arranged to rotate the valve at the proper relative speed to admit the charge and to permit the exhaust at the 55 proper time.

We claim:

1. An engine of the character specified, comprising a shell having open ends, a crank case at the lower end of the shell, a 60 crank shaft journaled in the case, a cylinder in the shell, said cylinder extending into the crank case, and having its outer end recessed to form one section of a bearing, an outer bearing section secured to the outer

end of the shell and coöperating with the 65 inner section to form a cylindrical valve chamber, said sections being spaced apart, a cylindrical valve in the chamber and extending beyond the same at each end, a head at one end of the valve fitting against the 70 end of the chamber, a ring of teeth on the other end of the valve, a sprocket wheel on the crank shaft, a chain connecting the wheel to the ring, said sections each having a pair of alined ports extending longitudinally of the valve and registering with the 75 ports of the other section, and the valve having diametrical passages for connecting the registering ports of the sections, a piston in the cylinder, a connection between the 80 piston and the crank shaft, and means for pressing the cylinder outwardly toward the valve, said means comprising an elbow lever pivoted in the crank case and having resilient arms arranged at an angle to each 85 other, one of said arms engaging the inner end of the cylinder, and a set screw threaded through the crank case and engaging the other arm.

2. An engine of the character specified, 90 comprising a shell having open ends, a crank case at the lower end of the shell, a crank shaft journaled in the case, a cylinder in the shell, said cylinder extending into the crank case, and having its outer end recessed to form one section of a bearing, an 95 outer bearing section secured to the outer end of the shell and coöperating with the inner section to form a cylindrical valve chamber, said sections being spaced apart, a cylindrical valve in the chamber and extending beyond the same at each end, a head at one end of the valve fitting against the end of the chamber, a ring of teeth on the other end of the valve, a sprocket wheel on the crank shaft, a chain connecting the wheel to the ring, said sections each having a pair of alined ports extending longitudinally of the valve and registering with the 100 ports of the other section, and the valve having diametrical passages for connecting the registering ports of the sections, a piston in the cylinder, a connection between the piston and the crank shaft, and means for pressing the cylinder outwardly toward the 105 valve, and means for adjusting the pressure of the said means.

3. An engine comprising a shell and a crank case, a cylinder in the shell and extending into the crank case, the outer end 120 of the cylinder being recessed on its outer face to form the inner section of a cylindrical valve chamber having its axis at right angles to the axis of the cylinder, an outer section connected to the end of the shell 125 and spaced apart from the inner section, a cylindrical valve in the chamber, said sections having registering alined longitudi-

nally extending ports, and the valve having passages arranged at an angle to each other for connecting the registering ports, and yielding means normally pressing the 5 cylinder toward the outer section, said means comprising an angle lever pivoted in the crank case and having a resilient arm engaging the inner end of the cylinder, an adjustable set screw engaging the other arm 10 of the lever, a piston in the cylinder, and a driving connection between the piston and the valve for rotating said valve.

4. An engine comprising a shell and a crank case, a cylinder in the shell and extending into the crank case, the outer end of the cylinder being recessed on its outer face to form the inner section of a cylindrical valve chamber having its axis at right angles to the axis of the cylinder, an 15 outer section connected to the end of the shell and spaced apart from the inner section, a cylindrical valve in the chamber, said sections having registering alined longitudinally extending ports, and the valve 20 having passages arranged at an angle to each other for connecting the registering ports, yielding means normally pressing the cylinder toward the outer sections, and means for varying the tension of the said 25 means, a piston in the cylinder, and a connection between the piston and the valve for rotating said valve.

5. In an engine, the combination with the shell having open ends and the piston, of a cylinder between the shell and the piston, a cylindrical valve chamber at the outer end of the shell, said chamber having its axis at right angles to the axis of the cylinder and being composed of inner and outer sections 30 spaced apart from each other, the inner section being integral with the cylinder, and the outer section being secured to the shell, yielding means pressing the sections together, and means for varying the tension of 35 the said means.

6. In an engine, the combination with the shell having open ends and the piston, of a cylinder between the shell and the piston, a cylindrical valve chamber at the outer end 40 of the shell, said chamber having its axis at right angles to the axis of the cylinder and composed of inner and outer sections, the outer section being secured to the shell and the inner section to the cylinder, yielding 45 means pressing the cylinder toward the outer section, means for varying the pressure of the said means, and a valve rotatable in the chamber and operated by the piston.

7. In an engine, the combination with the 50 shell having open ends and the piston, of a cylinder between the shell and the piston, a cylindrical valve chamber at the outer end of the shell, said chamber having its axis at right angles to the axis of the cylinder and

composed of inner and outer sections, the 65 outer section being secured to the shell and the inner section to the cylinder, yielding means pressing the cylinder toward the outer section, and a valve rotatable in the chamber and operated by the piston. 70

8. In an engine, the combination with the shell and the piston, of a cylindrical valve chamber at the outer end of the shell and at right angles thereto, a valve rotatable in the chamber, said chamber being composed 75 of sections spaced apart from each other, a cylinder between the piston and the shell, one section of the chamber being connected to the cylinder and the other to the shell, yielding means pressing the cylinder toward 80 the outer section, and means for varying the pressure of the said means.

9. In an engine, the combination with the shell and the piston, of a cylindrical valve chamber at the outer end of the shell and at 85 right angles thereto, a valve rotatable in the chamber, said chamber being composed of sections spaced apart from each other, a cylinder between the piston and the shell, one section of the chamber being connected to 90 the cylinder and the other to the shell, and yielding means pressing the cylinder and the chamber section connected therewith toward the chamber section connected to the cylinder. 95

10. In an engine, the combination with the shell and the piston, of a valve chamber at the outer end of the shell, a valve rotatable in the chamber, said chamber being composed of sections spaced apart from each other, a cylinder between the piston and the shell, one section of the chamber being connected to the cylinder and the other to the shell, and yielding means pressing the cylinder and the chamber section connected therewith toward the chamber section connected 100 with the shell. 105

11. An engine comprising a shell, a cylindrical valve chamber arranged at one end of the shell and having its axis at right angles 110 to that of the shell, a cylindrical valve in the chamber, said valve having a marginal flange at one end fitting against the end of the chamber, and being provided with an annular series of teeth at the other end, a crank 115 shaft, a piston in the shell connected to the shaft, a sprocket wheel on the crank shaft, a chain connecting the wheel to the teeth of the valve, said chamber having a pair of oppositely arranged registering exhaust and 120 inlet ports leading into the chamber and from the chamber to the shell, the valve having diametrical passages for connecting the pairs of registering ports, a cylinder between the piston and the shell, the chamber being 125 composed of sections spaced apart from each other, one section being connected to the shell and the other to the cylinder, and yield-

ing means pressing the cylinder toward the outer section.

12. In an explosion engine, a cylinder, an inner bearing section connected to the cylinder, a shell inclosing the cylinder, an outer bearing section connected to the shell, and resilient means pressing the cylinder and the

inner section toward the outer section, said means being adjustable to vary the pressure.
